UNITED STATES PATENT OFFICE.

JOHANN STUMPF, OF BERLIN, GERMANY.

CONDENSER.

No. 825,281.

Specification of Letters Patent.

Patented July 3, 1906.

Application filed December 20, 1901. Serial No. 86,711.

To all whom it may concern:

Be it known that I, JOHANN STUMPF, a subject of the King of Prussia, German Emperor, and a resident of 27 Rankestrasse, Berlin, Kingdom of Prussia, German Empire, have invented new and useful Improvements in Condensers, of which the following is an exact specification.

My invention relates to a new and improved condenser in form of a turbine-wheel provided with a rim having buckets or vanes, around which rim a second non-rotatable so-called "leading-vane" rim is situated.

My invention is represented on the accompanying drawings, in which—

Figure 1 is a vertical section of the whole condenser. Fig. 2 is a vertical section of part of the turbine-wheel rim and the leading-bucket rim to an enlarged scale. Fig. 3 is a vertical section of a steam-turbine provided with my new condenser. Fig. 4 is a side view of the turbine shown in Fig. 3.

In case water or other liquid and air are brought into a turbine-wheel at or near the center of the same, the fluid will by the rotation of the wheel always be discharged through the bucket spaces or channels and will always flow along that wall of the channels which are situated opposite to the direction of rotation, or, in other words, the fluid will flow along the rear wall. A small passage will remain in every channel for the air, steam, or the like contained in the chamber in which the turbine-wheel rotates, which passage is situated between the water and that wall of the channel which is situated at that side in the direction in which the rotating turbine-wheel moves. The continual streams of air, steam, or the like and water escaping from the turbine-wheel are continually interrupted by the buckets of the same passing the fixed leading buckets or vanes of the outer rim. As soon as the channels of both bucket-rims are situated one above the other, or, in other words, momentarily register, the columns of water pass from the turbine-wheel into the channels between the leading buckets. At the next moment these columns of water are interrupted again by the turbine-wheel moving on. Now as air or steam continually passes to the leading-bucket rim and enters the channels of the same small quantities of air or steam are always inclosed or pocketed by quantities of water entering at the moment when the channels are situated one above the other. In

consequence thereof small disconnected columns of water are formed in the channels of the leading bucket, which columns of water drive the air, steam, gas, or the like contained fluid between them to the outer circumference of the leading bucket-rim by reason of the centrifugal force produced by the revolution of the turbine-wheel. This arrangement may be used for condensing steam as well as for pumping, or even for compressing air or the like gases. If air or gases are to be drawn off by means of this apparatus, it will be sufficient to have the channels of the leading-bucket rim of the same area all over, while in case the gases are at the same time to be compressed it will be necessary to construct the channels so that their area will diminish toward the outer circumference of the rim.

The apparatus may advantageously be used for condensing steam, as the columns of water formed during the rotation of the turbine-wheel within the channels of the leading-bucket rim cause a very fine distribution of the water, the steam being inclosed between the numerous small water columns, whereby a large surface is formed, on which surface the steam condenses.

Between the leading buckets the momentum of the water is transformed into effect by the velocity of the same being gradually reduced and at the same time the condenser-pressure is being augmented up to the pressure of the outer atmosphere. Around the outer leading-bucket rim a casing is provided, into which the water and the steam or the water of condensation are or is thrown, and from which casing it is led off through an out-flow-pipe.

The condenser arrangement above described has a great advantage over the condensers hitherto used, inasmuch as the pressure which is still contained in the water-inlet pipe is utilized. In the condensers hitherto used it is a great disadvantage that if, for instance, the condenser is situated, say, five meters above the level of the water which has to be pumped up, the suction force by means of which the water could be sucked up another five meters is not used at all. In using my new condenser this suction force is transferred into velocity as soon as the water enters the turbine-wheel. In this way the suction force has an advantageous effect upon the movement of this turbine-wheel. The motor for driving the turbine-wheel

needs, therefore, only so much power as the turbine-wheel needs additional power for overcoming part of the atmospheric pressure.

In case only a small quantity of water is used the apparatus may advantageously be constructed to form a condenser in which the same water is always used over again for condensing purposes, so that the water will always circulate. In order to attain this purpose, an annular space must be left free around the leading-bucket rim, through which annular space a cold air-stream is drawn by means of a revolving fan or the like ventilator. This current of cold air passes through the finely-distributed hot water and effects a quick evaporation of the same. The air-current thus saturated with steam is led off through an exhaust-pipe. By the evaporation the temperature of the water is reduced in the same degree as it was augmented within the turbine-wheel or within the channels between the leading buckets by the condensation of the steam. Hereby is attained that on the outside of the leading-bucket rim nearly the same quantity of water is vaporized, which quantity is formed within the channels of the leading-bucket rim by means of the condensation. The water once used and cooled again can be collected in a reservoir and from there be drawn back into the condenser. In this case the velocity corresponding to an air-pressure of about ten meters of water-pressure—that is to say, the pressure of about one atmosphere—is utilized for driving the turbine wheel, and only a very small quantity of additional power for driving this wheel is necessary, contrary to the condensers used until now, in which it is not possible to utilize the whole water-pressure.

A further advantage of the new condenser is the lack of all kinds of valves, which often render all kinds of repairs necessary in condensing apparatus. The condensers are especially advantageous and useful for steam-turbines. It is clear that all complicated driving mechanisms usually employed hitherto in condensing apparatus are now entirely perfectly superfluous.

In Figs. 1 and 2 of the drawings a condenser constructed according to my invention is shown. The water and air enter the turbine-wheel near the center of the same. The water is then divided up between the numerous buckets of the turbine-wheel rim and flows through the channels *m* between these buckets in separate columns *q*. It will be seen from the drawings that the water flows along that wall of the channels opposite to the direction in which the wheel rotates. By the water entering the leading-bucket rim columns of water are formed. A certain quantity of water passes from each channel *m* of the turbine-wheel in one of the channels *n* of the leading-bucket rim. In consequence of the continuous interruption of the con-

nection between the channels *m* and *n* more or less complete columns of water *l* are formed, between which columns air or (in case of a condenser) steam is inclosed, which steam condenses while being forced through the channels *n*. The steam can be admitted with the water near the center of the turbine-wheel; but it will be understood that it may equally well be admitted between the turbine-wheel and the leading-bucket rim. In Fig. 1 the latter arrangement is shown. The turbine-wheel *b* is fixed to the shaft *a*, which is rotated by means of a steam-turbine, an electric motor, or the like. Around the turbine-wheel *b* the leading-bucket rim *c* is arranged. The water enters the turbine-wheel by the pipe *d* and the chamber *f*. The steam enters by the vertical pipe *g* and passes through the pipes *h* and *o* to the turbine-wheel. It enters this wheel between the rim of the same and the leading-bucket rim. To the annular chamber *p*, provided around the leading-bucket rim, a channel *r* is connected, in which channel revolves a fan *s* or the like on the shaft *a*. This fan sucks a cold air-stream through the chamber *p*, so that the water leaving the leading-bucket rim *c* and entering this chamber is cooled. The water can then be collected underneath the condenser in a reservoir and can be brought back from there to the turbine-wheel. It will be understood that the apparatus described can also be used for removing the condensation water, steam, and air out of a so-called "surface-condenser."

In case the bucket-wheel of the condenser is fixed directly upon the shaft of the engine for which the condenser is provided a mechanical efficiency of one hundred per cent. can be attained. The condenser can most advantageously be used in connection with steam-turbines, in which case a bucket-wheel can be situated within the turbine-casing and fixed to the turbine-shaft. Besides the great efficiency this arrangement has the advantage that a special condensing vessel and herewith all the auxiliary means which are necessary for a separate condenser, which means are driven by the engine, are no longer necessary. The result hereof is naturally a very considerable simplification and cheapening of the whole arrangement. Furthermore, it must be taken in consideration that the way the steam has to pass from the turbine-wheel to the condenser is as small as possibly can be attained. An example of such an arrangement is shown in Figs. 3 and 4 of the accompanying drawings. The turbine-wheel *A*, with a relatively large diameter, is fixed within the closed casing *C* to a shaft *B*. Around the turbine-wheel *A* the steam-admission channel *D* is situated, from which the steam is led to the turbine-wheel through the admission-nozzles *D'*. In the drawings a turbine with double buckets, so-called "Pelton" 130

buckets, is shown, in which the steam enters in the middle between the two buckets and streams through the buckets to the sides. Upon the shaft B bucket-wheels E are arranged on both sides of the turbine-wheel A. These bucket-wheels E are surrounded by the fixed leading-shovel rims or buckets F. Each bucket-wheel forms with its leading-shovel rim a condenser in the manner described above, in which the cooling-water enters near the shaft, is divided up in the buckets of the bucket-wheel, and streams out in small water-plugs, between which steam to be condensed is situated, through the leading-shovel rim. The steam leaving the turbine-wheel A can flow within the casing C immediately to the condensers. This steam will come in contact with the cooling-water especially in the annular space situated between the bucket-wheel and the leading-shovel rim and will condense between the water-plug in the channels of the leading-shovel rim.

As may be seen from Fig. 3, the bearings G of the shaft B are situated in hollow casings H. The water which is led to the condenser flows through the casings H and hereby effects the cooling of the bearings G. The water is led to the turbine through pipes J and enters the casing C through annular nozzle-openings H', situated around the shaft B, flows then along the shaft B, and enters into the bucket-wheels E. The nozzles M are secured to the inner ends of the bearings H and serve to direct the incoming water along the hub of the wheels E, with sufficient velocity to prevent it from being thrown off centrifugally. In connection with this matter it should be borne in mind that the hub is smooth and that the coefficient of friction between it and the tubular stream of water discharged by the nozzle is very small. Any water discharged directly by the nozzle and not immediately picked up by the wheel will be caught by and carried along with the large volume of steam rushing through the spirally-arranged space bounded by the casing and the partition K. To state the matter in a different way, the steam or other elastic fluid discharged by the bucket-wheel A acts like an injector and carries the water in a more or less finely-divided state along with it. The action of the wheels E in discharging cooling-water causes the mixture of steam and water to be carried with it through the leading-shovel rims F. Owing to the fact that the chamber surrounding the wheel-hub is working at a vacuum, the cooling-water will continue to flow through the nozzle M if the wheel or pump E is primed, providing, of course, that the distance the water has to be raised is not too great. Where the distance is too great, a suitable pump may be employed in addition.

65 In those cases where it is desired to deliver

the cooling-water or other fluid directly to the pumps or wheels E without giving the steam an opportunity to come in contact therewith I may employ the chamber f, as shown in Fig. 1. It will be seen that the cooling-water is discharged in streams through small orifices in the wheels E, which causes it to mix intimately with and condense the steam or other motive fluid exhausting from the turbine-wheel. The partition K serves 75 to prevent exhaust-steam from continuously rotating with the bucket-wheel A and at the same time directs it toward the water-discharging wheel. The arrangement described is especially desirable, owing to its high efficiency. All of the parts are inclosed in the same casing, which dispenses with long passages, valves, &c. It also occupies a minimum amount of floor-space.

During the passage of the cooling-water 85 from the casing H to the bucket-wheels E it comes in contact with the steam and will partly condense the same. It will be clear that the bucket-wheels E can be provided with cut-outs or with similar arrangements, 90 so that while the water passes through them the steam can come in contact with the same and can be condensed.

Advantageously on both sides of the turbine-wheel a spiral-formed partition K is provided, as shown in Fig. 4 of the drawings. These partitions K have the purpose of facilitating the admission of the steam to those places in which the same is condensed by acting against the centrifugal power of the 100 steam leaving the turbine-wheel A with a considerable velocity. From the leading-shovel rims F the cooling-water and the condensed steam discharges into the annular room L and flows off from there through the 105 channels L'.

Having thus fully described the nature of my said invention, what I desire to secure by Letters Patent of the United States is—

1. In a condenser, the combination of a 110 turbine-wheel, means for rotating said turbine-wheel, a stationary leading-shovel rim situated around said turbine-wheel and means for leading water to the shovels of the turbine-wheel from the center of the same, 115 substantially as described and for the purpose set forth.

2. In a steam-turbine, the combination of a 120 turbine-wheel, means for leading steam to said turbine-wheel and a casing surrounding the turbine-wheel, of a second turbine-wheel rigidly connected to the shaft of the first turbine-wheel, a leading-shovel rim situated around said second turbine-wheel and means for leading cooling-water to the shovels of the 125 second turbine-wheel from the center of the same, substantially as described and for the purpose set forth.

3. In a steam-turbine, the combination of 130 the turbine proper, with several condensers

situated in the steam-turbine casing C, said condensers consisting of turbine-wheels E connected to the shaft B of the steam turbine - wheel A, leading-shovel rims F and 5 means for leading cooling-water to the shovels of the turbine-wheels E, substantially as set forth and for the purpose specified.

4. In a steam-turbine, the combination of the turbine proper, with several condensers 10 situated in the steam-turbine casing C, said condensers consisting of turbine-wheels E connected to the shaft B of the steam turbine-wheel A, leading-shovel rims F, means for leading cooling-water to the shovels of the 15 turbine-wheels E, and spiral-formed partitions K situated within the turbine-casing e so as to lead the exhaust-steam to the condenser, substantially as described and for the purpose set forth.

20 5. An elastic-fluid turbine comprising a casing and bucket-wheel, in combination with a wheel rotating with the bucket-wheel, buckets carried by a separate support which decrease the velocity of the fluid delivered by 25 the wheel, a chamber containing liquid to feed the wheel, and a conduit for supplying the chamber.

30 6. An elastic-fluid turbine comprising a bucket-wheel and casing in which the motive fluid is condensed after leaving the wheel, in combination with a pump which is located within the casing and is driven by the bucket-wheel, and buckets carried by a separate support and surrounding the wheel which decrease the velocity of the fluid discharged by 35 the wheel.

40 7. An elastic-fluid turbine comprising a casing and bucket-wheel in combination with a water-discharging wheel of smaller diameter than the bucket-wheel located in said casing for condensing the motive fluid after it passes through the bucket-wheel, and means for conveying the exhaust from the bucket-wheel to the water-discharging wheel where it mingles with the water.

45 8. An elastic-fluid turbine comprising a casing and a bucket-wheel in combination with a cylindrical structure located in said casing containing one or more velocity-reducing orifices through which cooling-water is discharged, and a device for directing the exhaust against said structure.

50 9. In a combined turbine and condenser, the combination of a wheel having driving-buckets, means for discharging fluid against the buckets, rows of buckets arranged on opposite sides of the driving-buckets, and conduits for conveying liquid to the last-men-

tioned buckets for condensing the exhaust from the first-mentioned buckets.

60 10. In a combined turbine and condenser, the combination of a wheel having driving-buckets, means for discharging fluid against the buckets, rows of buckets arranged on opposite sides of the driving-buckets, and of less 65 diameter, stationary buckets arranged to receive the fluid delivered by the last-mentioned buckets and decrease its velocity, and conduits for conveying liquid to the said rows of buckets to condense the exhaust from the 70 driving-buckets.

11. In a combined turbine and condenser, the combination of a wheel having driving-buckets, a second set of buckets driven by the first, a shaft for the buckets, a bearing 75 for the shaft, a nozzle carried by the bearing for directing a cooling liquid along the shaft to the second set of buckets, and a conduit for supplying liquid to said nozzle.

80 12. In a combined turbine and condenser, the combination of a wheel having driving-buckets, a casing therefor, a second set of buckets driven by the first, stationary buckets 85 receiving fluid from the driven buckets and decreasing its velocity, a casing supporting the stationary buckets and containing a chamber into which the latter discharge, and a conduit for exhausting the fluid from the chamber.

90 13. In a combined turbine and condenser, the combination of a wheel having driving-buckets, a casing therefor, a second set of buckets driven by the first, of smaller diameter than the first, stationary buckets receiving fluid from the second set and decreasing 95 its velocity, a means for conveying exhaust from the driving-buckets inward to the second set of buckets, and a conduit for conveying liquid to the driven buckets for condensing the exhaust from the driving-buckets.

100 14. In a combined turbine and condenser, the combination of driving-buckets, driven buckets mounted on the same shaft and on opposite sides of said driving-buckets, conduits for supplying liquid to the driven buckets, for condensing the exhaust from the driving-buckets, conduits which receive the condensed fluid from the buckets, and a receptacle which is common to the conduits.

110 In testimony whereof I have signed my name to this specification in the presence of two subscribing witnesses.

JOHANN STUMPF.
